BAND SEALING MACHINE

Walter Lee Owens, Chesterfield, Ind., assignor to
Robert W. Sheemaker, Anderson, Ind.

Application November 14, 1941, Serial No. 419,197

4 Claims.

(Cl. 81—9.1)

The invention relates to the banding of packages of sheet steel or other materials, and more particularly to a machine for sealing the steel bands or straps with which the packages are bound.

Sheets of steel are usually shipped from the mill in packages or bundles bound with steel bands or straps the ends of which are connected together by sheet metal seals.

The steel bands may be stretched around the bundle or package, of sheets or the like, by any suitable banding machine, which may be of the type shown in my Patent No. 2,247,398, dated July 1, 1941, by means of which the bands are strapped tightly around the bundle with the ends of the band overlapped to receive sheet metal seals which are usually crimped upon the overlapped ends of the bands to hold them tightly bound around the package.

Under present practice this sealing is performed by a device known in the trade as a sealing machine. Such sealing machines as are now in general use are large, heavy and cumbersome, and require both hands to operate the same, making it necessary for one man to operate the banding machine to stretch a band around the package while another man is required to operate the sealing machine.

Another objection to such sealing machines as are now in use is due to the fact that because of the manner in which such machines are constructed it is very difficult to crimp the seal where the bands and seal are flattened tightly against the package of sheets or other material to be banded. This is largely due to the fact that under present practice the sealing machines in use are designed to crimp or cut the seal and bands downward against the package.

It is an object of the present invention to provide a band sealing machine of comparatively light weight and so constructed that it may be operated with one hand while the operator uses the other hand to stretch the band with a banding machine or tool.

Another object of the invention is the provision of a band sealing machine which cuts the seal and band upward, whereby it may be entered under the edges of a seal regardless of how tightly the band may be stretched around the package.

A further object is the provision of such a band sealing machine in which the cutting edges are carried upon pivoted jaws arranged to engage beneath the seal and band.

A still further object of the invention is the provision of such a band sealing machine in

which the pivoted jaws are operated through toggle levers by a single operating handle or lever.

Still another object is the provision of a band sealing machine of the type referred to in which a central die portion is provided for clamping and mashing the central portion of the seal and adjacent portions of the band downward during the cutting or sealing operation.

Another object is the provision of such a band sealing machine in which the operating parts are mounted in a housing having a relatively fixed arm adapted to rest upon the package of sheets or other material being banded and a pivoted arm or handle for operating the machine.

15. A still further object of the invention is the provision of a machine of this type in which the pivoted jaws are connected by toggle levers to a rotatable disc to which the operating handle or lever is fixedly connected.

20. The above objects together with others which will be apparent from the drawings and following description, or which may be later referred to, may be attained by constructing the improved band sealing machine in the manner illustrated in the accompanying drawings, in which—

Figure 1 is a side elevation of the improved band sealing machine showing the same in the open position;

Fig. 2, a front end elevation of the band sealing machine in the position shown in Fig. 1;

Fig. 3, a longitudinal sectional view through the improved band sealing machine on a larger scale, showing the machine in the closed or operated position;

35. Fig. 4, a top plan view of the machine in the position shown in Fig. 3;

Fig. 5, a bottom plan view of the band sealing machine in the open position as shown in Fig. 1;

Fig. 6, a fragmentary elevation of the inner face of one jaw of the machine;

Fig. 7, an enlarged detailed perspective view of one of the cutting knives;

Fig. 8, a detached perspective view of one of the sheet metal seals;

45. Fig. 9, a fragmentary sectional view of a portion of the overlapped ends of a band showing the seal placed thereon in position for sealing, and

Fig. 10, a view similar to Fig. 9 after the seal and band have been cut and sealed by the improved band sealing machine.

Similar numerals refer to similar parts throughout the drawings.

The improved band sealing machine to which the invention pertains is mounted within a hous-

ing comprising the lower, central block 11 and the side plates 12 extending upwardly from each side of the block and connected thereto as by the pins 13.

The lower end of the block 11 is provided at its central portion with oppositely disposed flanges 14 having their edges slightly downwardly curved as at 15, and the lower ends of the side plates 12 are similarly downwardly curved at opposite edges as at 16, forming a die for clamping and mashing the central portion of the seal, and the adjacent portions of the overlapped ends of the band downward against the package of sheets or other material being banded.

A bifurcated arm 17 is rigidly attached to the lower portion of the housing thus formed as by the bolts 18, in position to rest upon the surface of the package being banded so as to hold the housing in vertical position as shown in Figs. 1 and 3.

A pair of similar jaws 19 is pivotally mounted between the side plates 12 of the housing. For this purpose each jaw may have an inwardly disposed boss 20 fitted within a curved recess 21 in the corresponding side of the block 11 and having a bearing opening 22 receiving the adjacent bolt 18 upon which the jaw is pivoted.

Each jaw 19 has a pair of cutting knives 23 preferably formed upon the pins 24 received in suitable openings 25 in the jaws. The cutting edge portion of each of these pins is located within an angular lateral recess 26 in the inner face of the jaw, terminating at its lower end in the tapered inwardly disposed lip 27. The cutting edges 23a, of these cutting knives, diverge upwardly from the lips 27 of the jaws, as shown quite clearly in Fig. 3, and each knife has a bevelled outer face 42, as best shown in Figs. 6 and 7.

An upwardly disposed lever portion 28 is formed upon each jaw and provided with spaced notches 29 at its upper end for receiving the adjacent ends of the toggle levers 30 which are pivotally connected to the levers 28 as by the pins 31. The opposite ends of the toggle levers 30 are received between the discs 32 and 33 to which they are pivotally connected as by the pins 34.

The discs 32 and 33 are mounted in spaced relation upon a bushing 35 fixed upon the shaft 36 which is journaled in the upper portions of the side plates 12 and provided at each end with a nut or head 36. The discs 32 and 33 are preferably rigidly connected together as by pin 37, and the operating handle or lever 38 is fixed to the central disc 32 so that movement of said handle from the raised position as shown in Fig. 1 to the lowered position as shown in Fig. 3 will cause the jaws 19 to be swung toward each other upon their pivots 18.

In forming a package of sheets or the like one or more sheet metal bands or straps as indicated at 39 may be placed around the package with the overlapped ends thereof inserted through a sheet metal seal 40 and the band is drawn tightly around the pack by any suitable form of banding machine or tool.

The sealing machine is then placed over the seal 40 in the position shown in Figs. 1 and 2, the central flanged portion of the block 11 resting upon the central portion of the seal 40. The rigid arm 17 rests upon the top of the package being banded, holding the sealing machine in vertical position.

While the workman operates the banding ma-

chine with one hand to stretch the band tightly around the package, with the other hand he pulls the lever 38 downward to the position shown in Fig. 3, engaging the tapered lips 27 of the jaws beneath the edges of the seal, the cutting edges 23a cutting opposite edge portions of the seal and band at spaced points as indicated at 41 in Fig. 10.

At the same time the beveled faces 42 of the cutters bend the edge portions of the seal and band upward at the outer sides of the cuts 41, as indicated at 43, while the flanged central portion of the block 11 clamps and mashes the central portion of the seal downward between said cuts, as indicated at 44. The band is thus held tightly strapped around the package and cannot be removed unless it is severed as by shears or the like.

From the above it will be evident that the improved sealing machine is simply and easily operated, being of such light weight and so constructed that it may be operated by one hand, leaving the other hand free to operate the banding machine or tool.

It will also be seen that the machine will work efficiently to quickly and easily seal a band even though the same may be stretched tightly against the surface of the package, as the tapered lips 27 of the jaws engage under the edges of the seal and the cutting edges 23a cut the seal and band upward while the block 11 holds the control portion of the seal and band down toward the package.

I claim:

1. A band sealing machine for fixing a seal upon the overlapped ends of a band, said sealing machine including a housing having a lower portion for contacting the longitudinal, central portion of the seal and spaced, lateral extensions for contacting opposite side edges of the seal at the center and at both ends of the seal, a pair of jaws pivotally mounted in the housing and having tapered lips for engaging under opposite side edges of the seal, spaced cutting knives upon the jaws diverging upwardly from the lips and having bevelled outer faces for cutting into opposite side edges of the seal between said lateral extensions on the lower portion of the housing and bending the seal upward at the outer side of each cut and means for simultaneously moving both jaws toward or from each other.

2. A band sealing machine for fixing a seal upon the overlapped ends of a band, said sealing machine including a housing having a lower portion for contacting the longitudinal, central portion of the seal and spaced, lateral extensions for contacting opposite side edges of the seal at the center and at both ends of the seal, a pair of jaws pivotally mounted in the housing and having tapered lips for engaging under opposite side edges of the seal, spaced cutting knives upon the jaws diverging upwardly from the lips for cutting into opposite side edges of the seal between said lateral extensions on the lower portion of the housing, beveled outer faces on said cutting knives for bending the edge portions of the seal upward at the cuts, and means for simultaneously moving both jaws toward or from each other.

3. A band sealing machine for fixing a seal upon the overlapped ends of a band, said sealing machine comprising a housing including a block and side plates rigidly connected to opposite sides of the block and extending upwardly therefrom, the lower end of the block and side plates con-

tacting the central, longitudinal portion of the seal, and spaced, oppositely disposed lateral extensions upon the lower portions of the block and side plates terminating in downwardly curved ends for engaging over the side edges of the seal, a pair of jaws pivotally mounted between the side plates and having opposed, tapered lips for engaging under opposite side edges of the seal, spaced cutting knives having cutting edges diverging upwardly from each lip for cutting upwardly into opposite side edges of the seal between said spaced, oppositely disposed extensions, upwardly extending lever arms fixed upon the jaws, a shaft journaled in said side plates, a disc fixed upon the shaft, toggle levers pivotally connected to the upper ends of the lever arms and to diametrically opposite points on the disc and an operating lever fixed to the disc.

4. A band sealing machine for fixing a seal upon the overlapped ends of a band, said sealing

machine including a housing having a lower portion for contacting the longitudinal, central portion of the seal and spaced, oppositely disposed lateral extensions upon the lower portion of the housing terminating in downwardly curved ends for engaging over the side edges of the seal, a pair of jaws pivotally mounted in the housing and having tapered lips for engaging under opposite side edges of the seal, spaced cutting knives having cutting edges diverging upwardly from each lip for cutting upwardly into opposite side edges of the seal between said spaced, oppositely disposed extensions, upwardly extending lever arms fixed upon the jaws, a shaft journaled in the upper portion of the housing, a disc fixed upon the shaft, toggle levers pivotally connected to the upper ends of the lever arms and to diametrically opposite points on the disc, and an operating lever fixed to the disc.
